UNITED STATES PATENT OFFICE.

PALLED BERTRAM KROUT, OF NARBERTH, PENNSYLVANIA.

WIRE CLAMP.

Application filed September 2, 1924. Serial No. 735,267.

To all whom it may concern:

Be it known that I, PALLED BERTRAM KROUT, a citizen of the United States, residing at Narberth, in the county of Montgomery and State of Pennsylvania, have invented a certain new and useful Improvement in Wire Clamps, whereof the following is a specification, reference being had to the accompanying drawings.

My invention relates to devices for clamping in parallel and crossed relation wires, cables or ropes, such device including a block having two grooves, in transverse relation and extending to different depths therein; and a J-bolt adapted to have its short end hooked over both cables and having its long end screw threaded to engage a nut by which it is drawn into clamped position. In the form of my invention chosen for illustration; the long end of the J-bolt extends through said block, transversely to the axes of the grooves, in said block; but the short end of said bolt extends in a socket in said block and is thus held against accidental displacement.

My improvement is advantageous as compared with clamps of the prior art, in that it provides means to securely hold the two wires or cables in either crossed or parallel relation, by manipulation of but a single nut; whereas all other clamps known to me require the manipulation of at least two nuts upon two bolt ends projecting through a base plate. Moreover, my improved block, having but one hole through it, may be made of stronger construction with less material than the devices of the prior art, which feature is of considerable commercial importance because the cost of metal in such clamps is gaged in accordance with the weight thereof.

My invention includes various novel features of construction and arrangement hereinafter more definitely specified.

In said drawings; Fig. I is a plan view of a clamp conveniently embodying my invention; showing a pair of wires engaged thereby in right angular crossed relation.

Fig. II is a longitudinal side elevation of the structure shown in Fig. I.

Fig. III is a longitudinal sectional view of said structure, taken on the line III, III in Fig. I.

Fig. IV is a transverse side elevation of said structure.

Fig. V is a transverse sectional view of said structure, taken on the line V, V in Fig. I.

In said figures; the block 1, which is conveniently formed as a drop-forging of steel, 60 has two grooves, 2 and 3 in it, respectively extending to different depths and at right angles to each other. Said grooves are adapted to hold wires 5 and 6 of the same diameter, either in the crossed relation shown, 65 in which the wire 5 extends in the groove 2, and the wire 6 extends in the groove 3, or with both wires 5 and 6 in parallel relation, in the groove 2. In either position; the J-bolt 8 is hooked over both wires 70 5 and 6 with its short leg 9 extending in the socket 10 in said block 1, and with its long leg 11 extending through the hole 12, so as to be accessible from the back of the block, which serves as an abutment for the nut 75 14 which is engaged with the screw thread 15 on said leg 11.

Although I have illustrated a full size clamp adapted to rigidly secure, by means of a single three-eighth inch diameter bolt, two 80 wires or cables each three-eighths of an inch in diameter; it is to be understood that I do not desire to limit myself to those dimensions or to any other specific details of construction and arrangement herein set forth, 85 as it is obvious that various modifications may be made therein without departing from the essential features of my invention, as defined in the appended claims.

I claim:

1. In a wire clamp; the combination with a drop-forged steel block of elliptical configuration, having two grooves, in transverse relation and extending to different depths therein, and having, between said grooves, 90 extending transversely to the planes thereof and through said block, near one of the smaller ends thereof, a bolt hole; and having, between said grooves, extending transversely to the planes thereof, at the opposite smaller end of said block, a bolt socket, terminating within said block; and a J-bolt having its longer end screw threaded and fitted to extend through said hole and having its shorter end fitted to extend in said 95 socket; and a single nut fitted to said bolt screw thread; whereby a pair of wires may be clamped together, in the respective grooves, in transverse relation to each other, by tightening said single nut, and two wires 100 105 110

may be clamped together in parallel relation in said deeper groove by tightening said nut.

2. In a wire clamp; the combination with a metal block of elliptical configuration, having two grooves, in transverse relation and extending to different depths therein, and having, between said grooves, extending transversely to the planes thereof and through said block, near one of the smaller ends thereof, a bolt hole; and having, between said grooves, extending transversely to the planes thereof, at the opposite smaller end of said block, a bolt socket; a J-bolt having its longer end screw threaded and fitted to extend through said hole and having its shorter end fitted to extend in said socket; and a single nut fitted to said bolt screw thread; whereby a pair of wires may be clamped together, in the respective grooves, in transverse relation to each other, by tightening said single nut, and two wires may be clamped together in parallel relation in said deeper groove by tightening said nut.

25 3. In a wire clamp; the combination with a metal block having two grooves, in transverse relation and extending to different depths therein, and having, between said grooves, extending transversely to the planes thereof and through said block, near one end thereof, a bolt hole; and having between said grooves, extending transversely to the planes thereof, at the opposite end of said block, a bolt socket, terminating within said block; and a J-bolt having its longer end screw threaded and fitted to extend through said hole and having its shorter end fitted to extend in said socket; and a single nut fitted to said bolt screw thread; whereby wires may be clamped together, in the respective grooves, in transverse relation to each other, by tightening said single nut, and wires may be clamped together in parallel relation in said deeper groove by tightening said single nut.

40 4. In a wire clamp; the combination with a metal block having two grooves, in transverse relation and extending to different depths therein, and having, between said grooves, extending transversely to the planes thereof and through said block, near one end thereof, a bolt hole; and having, between said grooves, extending transversely to the planes thereof, at the opposite end of said

block, a bolt socket; a J-bolt having its longer end screw threaded and fitted to extend through said hole and having its shorter end fitted to extend in said socket; and a single nut fitted to said bolt screw thread.

5. In a wire clamp; the combination with a metal block having two grooves, in transverse relation and extending to different depths therein, and having, extending transversely to the planes of said grooves and through said block, near one end thereof, a bolt hole; and having, parallel with said hole, at the opposite end of said block, a bolt socket terminating within said block; a J-bolt having its longer end screw threaded and fitted to extend through said hole and having its shorter end fitted to extend in said socket; and a single nut fitted to said bolt screw thread; whereby a pair of wires may be clamped together, in the respective grooves, in transverse relation to each other, by tightening said single nut, and two wires may be clamped together in parallel relation in said deeper groove by tightening said nut.

6. In a wire clamp; the combination with a metal block having two grooves, in transverse relation and extending to different depths therein, and having, extending transversely to the planes of said grooves and through said block, near one end thereof, a bolt hole; and having, parallel with said hole, at the opposite smaller end of said block, a bolt socket; a J-bolt having its longer end screw threaded and fitted to extend through said hole and having its shorter end fitted to extend in said socket; and a single nut fitted to said bolt screw thread; whereby a pair of wires may be clamped together, in the respective grooves, in transverse relation to each other, by tightening said single nut, and two wires may be clamped together in parallel relation in said deeper groove by tightening said nut.

7. In a wire clamp; the combination with a metal block having two grooves, in transverse relation and having a bolt hole through said block, and a bolt socket terminating within said block; a J-bolt having its longer end screw threaded and fitted to extend through said hole and having its shorter end fitted to extend in said socket; and a single nut fitted to said bolt screw thread; whereby wires may be clamped together, in the respective grooves, in transverse relation to each other, by tightening said single nut, and wires may be clamped together in parallel relation in either groove by tightening said single nut.

In testimony whereof, I have hereunto signed my name at Philadelphia, Pennsylvania, this thirtieth day of August, 1924.

PALLED BERTRAM KROUT.
